Primary Examiner — Raphael Barkai*Assistant Examiner* — Randall Gholson(74) *Attorney, Agent, or Firm* — Patterson Thuente Christensen Pedersen, P.A.**CLAIM**

The ornamental design for a mount for electronic display, as shown and described.

DESCRIPTION

FIG. 1 is a front perspective view of a mount for electronic display according to a first embodiment of the invention; FIG. 2 is a front elevation view of the mount for electronic display depicted in FIG. 1;

FIG. 3 is a right side elevation view of the mount for electronic display depicted in FIG. 1;

FIG. 4 is a left side elevation view of the mount for electronic display depicted in FIG. 1;

FIG. 5 is a top plan view of the mount for electronic display depicted in FIG. 1; and,

FIG. 6 is a bottom plan view of the mount for electronic display depicted in FIG. 1.

The rear elevation of the mount depicted in FIGS. 1-6 is not claimed, and is hence not depicted.
